UNITED STATES PATENT OFFICE.

GEORGE E. CLAUSS, OF ANSONIA, CONNECTICUT, ASSIGNOR TO THE ANSONIA O & C COMPANY, OF ANSONIA, CONNECTICUT.

ELASTIC WEBBING.

Application filed September 25, 1926. Serial No. 137,723.

This invention relates to elastic webbing, primarily but not necessarily intended for use in wide webs for the manufacture of corsets, girdles and the like.

5 One of the main objects is to provide a wide elastic web suitable for corset manufacture and for being cut up into various regular and irregular shapes, having an ornamental reticulated outer face suitable for 10 the exterior of the corset, a soft inner face suitable for the inner surface of the corset, and combining with these characteristics maximum flexibility, strength and porosity to air for purposes of ventilation.

15 Another object is to provide an elastic web having the ornamental reticulated outer face, and the soft inner face in which the component parts are strongly bound together, and which can be securely sewed 20 through its body to the part to which it is to be attached.

To these and other ends the invention consists in the novel features and combinations of parts to be hereinafter described and 25 claimed.

In the accompanying drawings:

Fig. 1 is a greatly enlarged somewhat diagrammatic outer face view of a web constructed in accordance with this invention;

30 Fig. 2 is an edge view looking from the left of Fig. 1, and

Fig. 3 is an edge view looking from the bottom of Fig. 1.

In the practice of my invention, I prefer 35 to use a single layer of covered elastic cords forming a part of the warp. These elastic cords form the longitudinal sides of a multiplicity of rectangles or reticules, made up into a large number of identical patterns. In 40 the particular form shown, there are nine reticules in a pattern, and Fig. 1 shows one complete pattern unit with an extra elastic warp cord at one side, and an extra filling pick at one end.

45 The drawing shows four covered rubber warps, 1, 5, 9 and 1^a arranged in the same plane in a single layer. Between the left-hand pair of elastic cords (Fig. 1) are illustrated three textile binder warps 2, 3, 4, respectively, constituting in this case the only textile warps between the covered rubber cords 1, 5. Between the cords 5 and 9 similar textile warps 6, 7, 8, are interposed, and between the cords 9 and 1^a, textile warps

10, 11 and 12 are located. In this particular instance, the reticules are formed by running a pair of filling picks A, B, across the warps at the lower end of the pattern, and similar pairs of filling picks E, F and I, J, above the picks A, B, at the proper intervals. The filling pick AA at the top belongs properly to the pattern next above, as illustrated in Fig. 1. It will be observed that each reticule is formed at the top and bottom respectively, by two parallel filling 65 picks, which in practice lie close together, the sides of the reticules being formed by the elastic cords. These reticules are filled or stuffed by means of other filling picks exposed for the greater part of their lengths 70 on the back or inner surface of the web, as hereinafter described. Two filling picks C, D cross the reticules between the fillers E, B; and the filling picks H, G and K, L, are similarly arranged with reference to their 75 respective reticules. The picks A, B, E, F, I, J serve primarily as binders, and I therefore term them binder fillers. The filling picks C, D, G, H, K, L serve to form a soft surface on the back of the web, and I therefore term them back fillers.

80 It will be observed that the binder filler pick A passes over the elastic cords and under all of the textile warps. The pick B on the other hand passes under all of the 85 elastic cords and over all of the textile warps. The filler picks E, I are similar to pick A, and the filler picks F, J are similar to the pick B in their arrangement. The back fillers which present the soft back 90 surface, are located for the main portion of their length at the back of the web, and only at rare intervals go up into the web body to pass over a binder. Preferably they pass over and are held by textile warps only, 95 being located beneath all of the elastic cords, as shown, but I do not limit myself in all aspects of the invention to this particular disposition. The back filler pick C, for example, passes over and is held by the textile 100 binder warp 11, but by no other binder warps in the pattern, although some changes may be made in this respect also, it only being required that the back filler picks be held by the warps at comparatively long intervals. 105 In the case illustrated, the back filler pick D passes over the warp 3 only, in one pattern unit. The back filler pick G is held only

- by the warp 7, so as to be caught and held at a point offset from the holding points of the picks G, D, and the back filler pick L is also caught and held by the warp 7. 5 The back filler pick K is held by the binder warp 3, and the back filler pick H by the binder warp 11.
- For the elastic cords, I preferably use single threads of 34 rubber, covered with 10 two layers of cotton yarn. The rubber threads are covered while under moderate tension and are held in tension by the covering, so that when the web is cut these elastic cords do not draw up and distort the fabric. When these elastic cords are removed from a piece of web they will preferably be of substantially the same length as the piece of web from which they were removed. This obviates the use of much or any sizing. 15 In order to make the web lie flat, which sizing would have a tendency to reduce the softness of the web. It is preferable in a web of this character to have a minimum amount of sizing. The binder picks are 20 preferably arranged in pairs, as above stated, although not necessarily so in all cases. The textile warps, which are all binders, may be conveniently formed of two threads of 26 hard twisted cotton yarn, twisted together 25 to make up a so-called 26-2 warp yarn. Each binder filling pick is preferably formed of two threads of 19/2 soft twisted yarn, delivered together by the shuttle to constitute one pick, these threads being woven 30 substantially parallel to each other. Twisting together of these threads may occur to a certain extent as an incident of manufacture, but the intention is to have them substantially parallel. The binder filling picks 35 have sufficient strength and at the same time considerable bulk, and the individual binder picks will be preferably about three times as bulky as the respective textile warps. The back filling picks used for creating the 40 soft back surface are, on the other hand, preferably bulkier than the binder filling picks. In the particular case illustrated, the picks C, D etc., which pass through the centers of the reticules, are each made up 45 of three threads of 19/2 soft twisted yarn, these threads being delivered together by the shuttle as one pick in a single traverse of the shuttle and woven in substantially parallel relation. Thus, in this instance, the back 50 filling picks C, D, etc. are each about 50% bulkier than the respective binder filling picks A, B, etc., and are approximately four and one-half times as bulky as the textile warps 2, 3, 4, etc. Due to this fact and the 55 method of holding the back filling picks in the web, they present a back web surface of a soft velvety character, notwithstanding the use of the elastic cords and the relatively thin and hard textile warps. Owing to the 60 fact also that the filling picks C, D, etc., and

also preferably the picks A, B, etc., are each constituted by substantially parallel threads, the web is given added flexibility. The arrangement of the back filling in the centers of the reticules is also such as to make the reticule centers porous, thus providing proper ventilation.

In the operation of forming the web, one of the loom shuttles weaves two picks of a filling of one character, e. g., binder filling, 7 and the second shuttle weaves two picks of another character, e. g., back filling. This sequence is then repeated indefinitely. The binder filling, as above stated, produces cross ribs in the web and also has a strong binding effect. The back filling not only provides a soft back on the web but has, in addition, a certain spacing effect. The web may have a selvage of any suitable character.

The web of my invention has a warp in which all the threads are strong. The back filling picks should obviously be woven into the web with very little tension so as to increase the softness of the inner face of the web. This also increases the porosity of the central parts of the reticules formed by the elastic cords in combination with the dense cross ribs. The cotton covering of the rubber cord is preferably such that the cross section of the cord is about three times that of the rubber inside, which is usually about $\frac{1}{2}$ and of an inch square. The twist in the individual threads of yarn used in the filling should be considerably less than that of the twist in the individual threads of the textile warps.

While in the preferred form each pattern unit contains three covered rubber warp cords, nine binder warp threads, six binder filling picks, and six back filling picks, it will be understood that these numbers, the sizes of the threads, and the arrangement thereof, are susceptible of considerable variation within the scope of the invention, and various other changes may be made in the details without departing from the principles of the invention as defined in the claims.

What I claim is:

1. A web containing covered rubber warp cords, textile binder warp threads, binder filling picks cooperating with the aforesaid elements to produce a strong binding effect in the web, and a reticulated surface thereon, and other filling picks, passing outside and back of a plurality of adjacent warp threads to form a soft back surface for the web, and held therein at relatively infrequent intervals by certain of the binder warp threads.

2. An elastic web comprising elastic warp cords in a single layer, textile binder warp threads, binder filling picks above and below the warp cords cooperating with the aforesaid elements to produce a strong binding effect in the web, and back filling

5 picks passing back of a plurality of adjacent warp threads to form a soft back surface on the web.

6 3. An elastic web comprising elastic warp
7 cords in a single layer, textile binder warp
8 threads, binder filling picks cooperating
9 with the aforesaid elements to produce a
10 strong binding effect in the web, and back
11 filling picks passing outside of a plurality
12 of adjacent warp threads to form a soft
13 back surface on the web, said back filling
14 picks being bulkier in the aggregate than
15 the binder filling picks.

16 4. An elastic web comprising elastic warp
17 cords, a plurality of textile binder warp
18 threads interposed between each pair of
19 elastic cords, binder filling picks above and
20 below the warp cords, and soft back filling
21 picks held at infrequent intervals in the
22 web and floated outside of a plurality of
23 adjacent warp threads to be exposed on the
24 back thereof for the greater part of their
25 length.

26 5. An elastic web comprising elastic warp
27 cords, a plurality of textile binder warp
28 threads interposed between each pair of
29 elastic cords, binder filling picks, and soft
30 back filling picks held at infrequent intervals
31 in the web and exposed on the back thereof
32 for the greater part of their length,
33 said back filling picks being individually
34 bulkier than the binder filling picks.

35 6. An elastic web comprising elastic warp
36 cords, a plurality of textile binder warp
37 threads interposed between each pair of
38 elastic cords, binder filling picks, and soft
39 back filling picks held at infrequent intervals
40 in the web and exposed on the back thereof
41 for the greater part of their length, said
42 back filling picks being individually bulkier
43 than the binder filling picks, and at least
44 equaling the same in number.

45 7. An elastic web comprising spaced
46 elastic warp cords, a plurality of textile
47 binder warp threads interposed between
48 each pair of elastic cords, binder filling
49 picks arranged in groups so as to form cross
50 ribs, and soft back filling picks lying below
51 all the rubber cords extending across the
52 web between the cross ribs.

53 8. An elastic web comprising elastic warp
54 cords, a plurality of textile binder warp
55 threads interposed between each pair of
56 elastic cords, binder filling picks arranged
57 in groups so as to form cross ribs, and soft

58 back filling picks extending across the web
59 between the cross ribs, said back filling picks
60 being bulkier in the aggregate than the
61 binder filling picks.

62 9. An elastic web comprising elastic warp
63 cords, a plurality of textile binder warp
64 threads between each pair of warp cords,
65 binder filling picks arranged in pairs, one
66 above and one below the warp cords, said
67 binder filling picks being strongly bound
68 into the web and producing cross ribs there-
69 in, and soft back filling picks floated outside
70 of a plurality of adjacent warp threads to
71 be exposed on the back of the web for the
72 greater portion of their length and crossing
73 the spaces between the ribs.

74 10. A web containing covered rubber
75 warp cords, textile binder warp threads,
76 binder filling picks bulkier than the warp
77 threads, and back filling picks bulkier than
78 the binder filling picks, said back filling
79 picks exposed for the major part of their
80 length on the back of the web to form a
81 soft back surface therefor, and held in the
82 web at relatively infrequent intervals by
83 certain of the binder warp threads.

84 11. A web containing covered rubber warp
85 cords, textile binder warp threads, binder
86 filling picks bulkier than the warp threads,
87 and back filling picks bulkier than the
88 binder filling picks, said back filling picks
89 exposed for the major part of their length
90 on the back of the web to form a soft back
91 surface therefor, and held in the web at
92 relatively infrequent intervals by certain of
93 the binder warp threads, said binder filling
94 picks being arranged in groups to form
95 dense cross ribs, creating in connection with
96 the warp cords, a reticulated front surface
97 on the web.

98 12. An elastic web comprising elastic
99 warp cords, textile binder warp threads,
100 binder filling picks above and below the
101 warp cords cooperating with the aforesaid
102 elements to produce a strong binding effect
103 in the web, and back filling picks floated
104 outside of and below a plurality of binder
105 warp threads to form a soft back surface
106 on the web, said binder filling picks travers-
107 ing the web in spaced groups so as to form
108 dense cross ribs and reticules on the front
109 face of the web.

110 In witness whereof, I have hereunto set
111 my hand this 20th day of Sept., 1926.

112 GEORGE E. CLAUSS.
